UNITED STATES PATENT OFFICE.

ANDREW WINEMAN, OF DETROIT, MICHIGAN.

DOSE-MEASURING BOTTLE.

1,044,719.

Specification of Letters Patent. Patented Nov. 19, 1912.

Application filed November 13, 1911. Serial No. 659,919.

To all whom it may concern:

Be it known that I, ANDREW WINEMAN, a citizen of the United States, residing at Detroit, county of Wayne, State of Michigan, have invented a certain new and useful Improvement in Dose-Measuring Bottles, and declare the following to be a full, clear, and exact description of the same, such as will enable others skilled in the art to which it pertains to make and use the same, reference being had to the accompanying drawings, which form a part of this specification.

This invention relates to dose measuring receptacles and has for its object a receptacle or bottle which is especially designed for travelers in order that a spoon may be dispensed with.

The construction of the bottle is such that the main stopper acts also as a closure for the dose measuring compartment, so that when the dose enters therein, it may be confined there until it has been taken by the user, who applies his lips to the aperture closed by a second and smaller stopper.

In the drawings:—Figure 1, is a vertical section of the bottle. Fig. 2, is a vertical section of a modified form.

1, is a bottle of ordinary shape, provided with a neck 2 that has a suspended portion 3. At one side and at the top, the bottle is provided with an aperture 4 which leads into a portion of the bottle interior, which is partitioned off into a separate compartment by the partition 5 that joins the side 35 of the bottle wall with the depending neck extension 3. A passage 6 leads from the compartment 7 to the interior of the neck portion, so that when the main stopper 8 is pushed down, it acts as a closure for the 40 passage 6.

When it is desired to fill the dose measuring compartment, the stopper 8 is raised slightly so as to bring it above the passage 6, the bottle is then tilted and some of its 45 contents allowed to run into the compartment 7, when the stopper again is pushed down, thereby closing the compartment. When it is desired to take the dose, the user removes the small stopper 9 that engages in the aperture 4 and applies his lips to this aperture. This compartment may be made in various shapes, it depending on the use to which the bottle is to be put. It may be made to hold a teaspoonful, or two tea-

spoonfuls, or it may be used to hold a table- 55 spoonful, or graduations may be placed upon the wall of the bottle adjacent this compartment to represent different measurements.

Fig. 2, shows the same invention embodied in a bottle of somewhat different design. In this bottle the suspended neck portion 3 is omitted, while the partition 5 is formed when the bottle is being manufactured by inserting a piece of metal through 60 the side wall of the bottle causing that wall to double upon itself as shown at 5^a, leaving the passage at 6. This affords a convenient and cheap method of manufacture. The stopper 8 comes down below the passage 6, 70 and also acts as a closure therefor. Otherwise the measuring compartment is the same as in Fig. 1.

What I claim is:—

1. A dose measuring receptacle, having in 75 combination a receptacle provided with a neck, a separate compartment opening into the receptacle portion proper at or near the neck, an ordinary stopper, such as a cork or a wooden or rubber plug, adapted to control 80 the main passage through the neck and also control the passage from the neck into the compartment and a stopper adapted to close the aperture leading from the outside into said compartment, substantially as de- 85 scribed.

2. In a bottle, a body portion and a neck portion, a partition in the body portion forming with the wall of the body portion a dose measuring receptacle, said measuring 90 receptacle having a lateral inlet opening in substantial alignment with the wall of the neck portion, and the wall of the body portion having an outlet opening for said receptacle, and a stopper for the neck portion of the bottle, said stopper being of a length to overlie the inlet opening of the measuring receptacle and adapted to slide in said neck whereby to expose the inlet opening of the measuring receptacle while 95 maintaining closed the neck of the bottle.

In testimony whereof, I sign this specification in the presence of two witnesses.

ANDREW WINEMAN.
